UNITED STATES PATENT OFFICE.

CARL ESCHENBRENNER, OF OBERLAHNSTEIN, GERMANY.

SEWER-PIPE.

No. 873,851.

Specification of Letters Patent.

Patented Dec. 17, 1907.

Application filed August 30, 1906. Serial No. 332,584.

To all whom it may concern:

Be it known that I, CARL ESCHENBRENNER, a subject of the German Emperor, and resident of Oberlahnstein, Germany, have invented certain new and useful Improvements in Sewer-Pipes, of which the following is a specification.

The present invention relates to a construction of sewer-pipes, which can be used while 10 road making and the like advantageously, and especially where space for covering a sewer is limited and where earthen-ware or metallic pipes cannot be laid owing to their high girth.

15 At the present time where pipes cannot be employed for the construction of sewers, bricks or stamped concrete blocks of rectangular shape and iron plates for covering the sewers are used which, owing to the necessity of a continued control of labor during 20 the manufacture of the sewer blocks and laying the blocks down as sewer, is highly disadvantageous.

The present invention removes the said 25 disadvantages by the essential parts of a sewer being manufactured apart and delivered to the plot as partially ready pieces, for a sewer, which is then a simple matter to lay the pieces down in the form of a sewer 30 and complete it with a nominal and simple amount of labor.

The drawing shows the object of the invention as follows

Figure 1 is a cross section view of a complete sewer. Fig. 2 a ground plan, and Fig. 3 a longitudinal section view of a sewer.

The essential parts referred to are the abutments which consists of angular shaped

pieces *a* having iron toothed ribbons *b* projecting from one end of their angles which 40 goes to the horizontal line of a sewer, and the abutments are of such size and construction as shall suit the requirement. The abutments so prepared have then only to be laid down as sewer at any breadth required and 45 the intervening space, between the sides from where the iron toothed ribbons *b* project, filled up with concrete or the like as shall bind the abutments together aided by the said toothed ribbons, and should the 50 breadth of the space between the abutments be too great suitable pieces of wire-netting *d* and the like is laid, so that the sewer becomes strong, binding, and durable, and lastly the top of the sewer is covered with 55 any suitable material such as beton plates as shown.

I claim,

In the construction of sewers, the combination of the angular shaped abutment pieces 60 *a* adapted to build broad and narrow sewers, the iron toothed ribbons *b* projecting from a side of the angles of the abutment pieces adapted to lay in the intervening space 65 breadthwise which are filled up with concrete *c* and bind and strengthen the sewer, the wire netting *d* laid in the intervening space lengthwise which is filled up with the said concrete and the beton plate which is used for covering the sewer, substantially as 70 shown and described.

CARL ESCHENBRENNER.
